(57) **CLAIM**

The ornamental design for a vehicle headlight, as shown and described.

DESCRIPTION

FIG. 1 is a front perspective view of a vehicle headlight;
FIG. 2 is a rear perspective view of a vehicle headlight;
FIG. 3 is a front view of a vehicle headlight;
FIG. 4 is a rear view of a vehicle headlight;
FIG. 5 is an outboard side view of a vehicle headlight;
FIG. 6 is an inboard side view of a vehicle headlight;
FIG. 7 is a top view of a vehicle headlight;
FIG. 8 is a front perspective view of an illuminated vehicle headlight;
FIG. 9 is a front view of an illuminated vehicle headlight;
FIG. 10 is an outboard side view of an illuminated vehicle headlight;
FIG. 11 is a top view of an illuminated vehicle headlight; and,
FIG. 12 is a supplemental front perspective view of a vehicle headlight in the installed position on a vehicle.

Portions of the figures shown in diagonal lines are for illustrative purposes only and form no part of the claimed design.
